UNITED STATES PATENT OFFICE

2,425,918

AGITATOR NOZZLE

Carl S. Brown, Lakewood, Ohio, assignor to
 Glascote Products, Inc., Cleveland, Ohio, a corporation of Ohio

Application September 14, 1944, Serial No. 554,094

1 Claim. (Cl. 259—18)

1

This invention relates to a nozzle and particularly to an agitator nozzle. More specifically, the invention is concerned with the provision of an agitator nozzle which may be projected into a tank or other container, secured to the walls thereof, and subsequently adjusted to direct the flow of liquid from the nozzle without requiring access to the interior of the container or removal of the nozzle from the walls thereof. These, therefore, are the general objects of the present invention.

A more specific object of the invention is to provide agitator nozzle which may be inserted through an opening in the outer or jacket wall of a jacketed container, secured in place as by welding, and thereafter adjusted to control the direction of the flow of fluid through the nozzle into the jacket space without requiring access to the space other than through the conduit leading to the nozzle.

Other objects and advantages of the invention will become more apparent from the following description, reference being had to a preferred embodiment of the invention illustrated in the accompanying drawings. The essential and novel features of the invention will be summarized in the claim.

Referring now to the drawings, Fig. 1 is a fragmentary sectional view of a jacketed container having my improved nozzle as applied thereto; Fig. 2 is an elevation of the nozzle looking in the direction indicated by the lines 2—2 on Fig. 1; Figs. 3 and 4 are sectional views of the nozzle, the planes of the sections being indicated by the correspondingly numbered lines on Fig. 3; and Fig. 5 is a section illustrating a different manner of attaching the nozzle to the tank.

In the drawings, I have illustrated my nozzle as applied to a jacketed tank, the internal wall of which is illustrated at 15, the external or jacket wall at 16. The jacket 16 is secured to the internal or tank wall by welds 17 and provides an enclosed jacket space 18. The wall 16 of the jacket is provided with an opening 19 through which a nozzle body 20 extends having a fluid passageway 26 extending axially therethrough. This body 20 is provided with a flange 21 which may be secured to the wall of the jacket, as by welds 22, to thereby completely close the opening 19, and provide a fluid tight permanent joint between

5 jacket wall and the nozzle body. The inner portion of the nozzle body 20 is reduced in cross section and is provided adjacent its end with internal threads 25 arranged to receive the threaded end portion 31 of a nozzle outlet 30.

The outlet 30 is provided with a fluid passageway 36 the inner portion of which forms a continuation of the body passageway 26, and the outer portion of which extends at right angles to the 10 passageway 26 to divert fluid into the jacket space. The member 30 may be rotated about the axis of the body member 20, as indicated by the dotted line position 30A in Figs. 1 and 4, to control the direction of flow of fluid from the 15 nozzle. The nozzle is particularly adapted for use in connection with jacketed containers in which fluid in the jacket space is utilized to cool or heat the contents of the container. In such installations it is often desirable to control the 20 direction of flow of fluid in the jacket space dependent upon the nature of the change of heat desired between the contents of fluid in the jacket space. In the construction shown in Figs. 3 and 25 4, the inner or threaded end 31 of a nozzle 30 is provided with slots 34 which may be engaged by a tool, projected through the longitudinal 30 opening or passageway 26 in the body 20, to facilitate rotating the nozzle to the desired position.

30 The external portion of the body 20 is threaded as at 27 to receive a coupling member, such as that indicated at 41 in Fig. 1, for connecting a conduit 40 with the nozzle.

In Fig. 5 is illustrated a different mode of attachment of the nozzle to the tank. Here a coupling 60 is welded to the exterior of the tank jacket and is provided with tapered internal threads 61 to coact with external tapered threads 62 formed on the body member 26. The tapered 40 threads provide a liquid tight joint between the body 20 and the tank and the slots 34 in the nozzle permit accurate positioning of the nozzle after such tight joint has been effected. A shield 70 may be secured to the internal wall of the jacket 45 16 to protect the tank wall from the effect of the jet and to prevent the nozzle from being inadvertently disconnected from the body 20.

From the foregoing description, it will be seen that I have provided a very simple and efficient 50 nozzle member which may be secured in place in

the walls of a receptacle with the nozzle member projecting inwardly of the wall, the position of the nozzle member being controlled from the exterior of the container through the medium of the fluid passageways through the nozzle.

I claim:

An agitator nozzle comprising a tubular body adapted and arranged to partially extend through an opening in the wall of a container or the like, a flange on said member for securing to such wall to close the opening therein and fasten the body thereon, said body having a fluid passageway extending therethrough to conduct fluid from one side of the wall to another, a nozzle member threadingly secured to said body member on one side of said wall, said nozzle being provided with slots accessible from the fluid passageway in said body for engagement by a tool passed through

said passageway therein to thereby facilitate adjustment of the position of said nozzle.

CARL S. BROWN.
